(57) **CLAIM**

The ornamental design for a reusable adhesive connector, as shown and described.

DESCRIPTION

FIG. 1 is a top plan view of the invention, showing my new design;

FIG. 2 is a bottom plan view of the invention;

FIG. 3 is a front elevational view of the invention, the rear elevational view, right side elevational view, and left side elevational view all being mirror image thereof;

FIG. 4 is a perspective view of a reusable adhesive connector; and,

FIG. 5 is a cross sectional view of the invention along 5—5 in FIG. 1.
